US0D1070569S

(12) **United States Design Patent** (10) **Patent No.:** **US D1,070,569 S**
(45) **Date of Patent:** **** Apr. 15, 2025**

(54) **MATTRESS FOUNDATION BRACKET**

(71) Applicant: **Ascion, LLC**, Bloomfield Hills, MI (US)

(72) Inventors: **Martin Bordley Bepko**, Rawls-Meehan, Birmingham, MI (US); **Kushan Nileshbhai Gajjar**, West Bloomfield, MI (US); **Qianyu Liang**, Rochester Hills, MI (US)

(73) Assignee: **Ascion, LLC**, Bloomfield Hills, MI (US)

(**) Term: **15 Years**

(21) Appl. No.: **29/912,250**

(22) Filed: **Sep. 15, 2023**

(51) LOC (15) Cl. **08-05**

(52) U.S. Cl.

USPC **D8/355**

(57) **CLAIM**

The ornamental design for a mattress foundation bracket as shown herein.

DESCRIPTION

FIG. 1 is a perspective view of a mattress foundation bracket in a raised position.

FIG. 2 is a front view of the mattress foundation bracket.

FIG. 3 is a rear view of the mattress foundation bracket.

FIG. 4 is a right-side view of the mattress foundation bracket.

FIG. 5 is a left-side view of the mattress foundation bracket.

FIG. 6 is a top view of the mattress foundation bracket.

FIG. 7 is a bottom view of the mattress foundation bracket; and,

FIG. 8 is a perspective view of the mattress foundation bracket in a lowered position.

The broken lines in the Figures are directed to unclaimed subject matter of the mattress foundation bracket and form no part of the claimed design.

1 Claim, 5 Drawing Sheets
